US00D696946S

(12) **United States Design Patent**
Hines

(10) **Patent No.:** **US D696,946 S**
(45) **Date of Patent:** **** Jan. 7, 2014**

(54) **METAL BOTTLE**

(71) Applicant: **Ball Corporation**, Broomfield, CO (US)
(72) Inventor: **Linda A. Hines**, Westminster, CO (US)
(73) Assignee: **Ball Corporation**, Broomfield, CO (US)
(**) Term: **14 Years**
(21) Appl. No.: **29/453,114**
(22) Filed: **Apr. 25, 2013**

(51) **LOC (10) Cl.** **09-01**
(52) **U.S. Cl.**

USPC **D9/500**; D9/558; D9/764

(58) **Field of Classification Search**

(57) **CLAIM**

The ornamental design for a metal bottle, as shown and described.

DESCRIPTION

FIG. 1 is a front perspective view of the metal bottle;
FIG. 2 is a top plan view thereof;

FIG. 3 is a front elevation view thereof;

FIG. 4 is a bottom plan view thereof;

FIG. 5 is a front perspective view of a metal bottle according to an alternative embodiment;

FIG. 6 is a top plan view of the embodiment of FIG. 5;

FIG. 7 is a front elevation view of the embodiment of FIG. 5;

FIG. 8 is a bottom plan view of the embodiment of FIG. 5;

FIG. 9 is a front perspective view of a metal bottle according to an alternative embodiment;

FIG. 10 is a top plan view of the embodiment of FIG. 9;

FIG. 11 is a front elevation view of the embodiment of FIG. 9;

FIG. 12 is a bottom plan view of the embodiment of FIG. 9;

FIG. 13 is a front perspective view of a metal bottle according to an alternative embodiment;

FIG. 14 is a top plan view of the embodiment of FIG. 13;

FIG. 15 is a front elevation view of the embodiment of FIG. 13;

FIG. 16 is a bottom plan view of the embodiment of FIG. 13;

FIG. 17 is a front perspective view of a metal bottle according to an alternative embodiment;

FIG. 18 is a top plan view of the embodiment of FIG. 17;

FIG. 19 is a front elevation view of the embodiment of FIG. 17;

FIG. 20 is a bottom plan view of the embodiment of FIG. 17;

FIG. 21 is a front perspective view of a metal bottle according to an alternative embodiment;

FIG. 22 is a top plan view of the embodiment of FIG. 21;

FIG. 23 is a front elevation view of the embodiment of FIG. 21;

FIG. 24 is a bottom plan view of the embodiment of FIG. 21;

FIG. 25 is a front perspective view of a metal bottle according to an alternative embodiment;

FIG. 26 is a top plan view of the embodiment of FIG. 25;

FIG. 27 is a front elevation view of the embodiment of FIG. 25;

FIG. 28 is a bottom plan view of the embodiment of FIG. 25;

FIG. 29 is a front perspective view of a metal bottle according to an alternative embodiment;

FIG. 30 is a top plan view of the embodiment of FIG. 29;

FIG. 31 is a front elevation view of the embodiment of FIG. 29;

and,

FIG. 32 is a bottom plan view of the embodiment of FIG. 29.

The broken lines in the drawings illustrate the portions of the

design that form no part of the claim.

1 Claim, 24 Drawing Sheets
